UNITED STATES PATENT OFFICE.

GEORGE DRAZICK, OF ESCANABA, MICHIGAN.

OPERATING MECHANISM FOR STUMP-PULLERS.

1,260,883.

Specification of Letters Patent. Patented Mar. 26, 1918.

Application filed January 31, 1916. Serial No. 75,299.

To all whom it may concern:

Be it known that I, GEORGE DRAZICK, a citizen of the United States, residing at Escanaba, in the county of Delta and State 5 of Michigan, have invented certain new and useful Improvements in Operating Mechanism for Stump-Pullers, of which the following is a specification:

My invention relates to stump extractors, 10 and more particularly the operating mechanism thereof, and is designed principally to provide a device of this character that will facilitate the easy and quick removal of the object to which it is applied.

15 The primary object of the invention is to provide a mechanism which will have a plurality of dogs or operating members operated from a single operating lever whereby through an adjustment any one or all of the 20 dogs may be brought into play, thereby varying the leverage obtained on the winding drum.

A further object of the invention is to 25 provide a device of this character which is simple in construction and capable of operation by manual power thereby avoiding the necessity of employing engine power.

Referring to the drawings;

Figure 1 is a view in elevation of the 30 stump-pulling machine constructed in accordance with the present invention.

Fig. 2 is a perspective view of one end of the power plug together with the means for restricting rotary movement thereof.

35 Fig. 3 is a detail view of two of the operating dogs.

Fig. 4 is a perspective view of the T-shaped member securing means for the dogs.

Fig. 5 is a sectional view of the power 40 plug and operating dogs, showing the T-shaped means for securing the dog thereto.

Fig. 6 is a perspective view showing the means for moving the operating dogs into and out of operation.

45 Fig. 7 is a plan view of the machine.

Fig. 8 is a plan view of the spring for holding the operating dogs under tension.

Fig. 9 is a sectional view taken on line 3-3 of Fig. 8.

50 Fig. 10 is an enlarged view of the operating mechanism with the top plate removed.

Fig. 11 is a sectional view of the cable drum with a portion thereof broken away.

Fig. 12 is a side elevational view of the power plug. 55

Fig. 13 is a wrench to be applied to the operating lever, and

Fig. 14 is a fragmental detail in section of the novel dog and the means for holding the same in disengaged position at times. 60

Referring more particularly to the drawings, the reference characters 5 and 6 designate upper and lower plates forming the frame of the machine, said frame being supported by means of wheels 1 and 2 carried on opposite ends of an axle 3 which in turn is secured to the frame. The plates are connected by bolts 7-8-9 and 10, the sleeves 11 being supported on their respective bolts and positioned between the upper 70 and lower plates for holding the same in spaced relation whereby the plates form a housing for the operating mechanism to be hereinafter more specifically described.

Each of the plates 5 and 6 has an extension 14 located centrally thereof and at right angles with relation thereto, the upper extension 14 having an apertured boss providing a bearing for one end of a power plug 15, the upper extremity of which is squared to receive an operating wrench 62 80 said squared upper end extending above the top plate and the opposite end thereof having a head 16 bearing against the under side of the supporting bar 16' which is suitably supported between bolts 8 and 9. 85

As clearly shown in Fig. 2 of the drawings, the lower end of the power plug 15 is suitably recessed and engages the cross bar 17 which has its ends extending through depending apertured lugs 18 provided on the under side of the supporting bar 16', and it will be seen that rotary movement of the power plug is, by this construction restricted due to the walls of the recessed portion 90 engaging the supporting bar 17 after the power plug has been moved a quarter turn in either direction.

As seen in Fig. 12 the power plug is provided intermediate its ends with a cut out 100 portion 19 the walls thereof being suitably shaped to receive the curved ends 20 of the dogs 21 and 22, the dog 22 having an upstanding lug 23 the purpose of which will be hereinafter more fully described. 105

Each of the dogs 21 and 22 is provided

with an opening 24, one of the walls of said opening being curved to receive the curved ends 25' of the T-shaped securing member 25, the base portion thereof being rigidly secured within the cut out portion 19 of the power plug 15 and it will be seen that due to the construction of the securing member 25, free pivotal movement of the dogs 21 and 22 is permitted.

10 Loosely secured to the power plug 15 is an operating lever 26 having one of its ends extending under the upper plate of the frame and lying in a position directly above the cable drum 12.

15 A dog 27 is pivotally connected to said end of the operating lever 26 and has its free end positioned to engage one side of the annular toothed flange 30 provided on the upper disk of the cable drum, said toothed flange having teeth on three sides thereof, the teeth on the opposite side being engaged by the free end of dog 28 which is also pivotally connected to operating lever 26, said free end extending beyond the dogs

25 27, whereby when the operating lever is rocked on its pivot, one dog engages the teeth of the flange 27 in advance of the other dog to accomplish a step by step movement of the cable drum. Each of the dogs 27 and 30 28 is provided with a lug 27' to which the opposite ends of a spring 29 are secured, whereby said dogs 27 and 28 are at all times held in engagement with the teeth of the flange 30.

Pivots secured to the under side of the operating lever 26, and positioned between the power plug 15 and the pivot point of dog 27 is a dog 31 which engages the upper teeth of the flange 30, while a suitable spring 31' is provided adjacent said dog for holding the same out of engagement with the upper teeth if it may be so desired.

A substantially semi-circular collar 33 is supported to rotate on the power plug 15 and it is obvious that by giving said collar a quarter turn by means of its handle 33', the dog 21 may be shoved into and out of operative position.

The bar 34 is pivotally supported by the depending lugs 35, one end of said bar extending at right angles with relation to the body thereof, the right angle end forming an operating lever or handle which engages within a notch 39 provided in the member 55 36, said handle being held in engagement with said notch by means of the coil spring 37 which is coiled around the shank of the pin 34, the central portion thereof being looped and engaged by a set screw 38' extending into the bar 34, the ends of said spring extending upwardly in parallel relation, one of said ends engaging the dog 21 while the opposite end engages dog 22, and it will be seen that by the tension of the 60 65 spring 37 the dogs 21 and 22 are held in

engagement with the outer teeth of said toothed flange until the tension of said spring is relieved, which is accomplished by releasing the operating handle from the notch 35.

Pivots supported by the bolt 8 is a lever 38 one of the ends thereof terminating in a handle 38' while the opposite end is curved to provide a cam 39 and it is also provided with an extension 40 for engagement with the lug 23 of dog 22 for moving the same out of operative position. 75

The cable drum 12 is provided with upper and lower extensions 50 and 51 fitted in suitable openings in the upper and lower plates said upper and lower extensions 50 and 51 forming the means by which the cable drum 12 is revolvably mounted between the plates 5 and 6, the upper extensions 50 being provided with a plurality of rack teeth 52 and said cable drum 12 is provided with a central bore 53 which terminates at its upper end in a constricted passage 54 through which the bolt 55 passes.

The lower end of the bolt 55 is provided with a washer 56 and interposed between said washer 56 and the upper end wall of the central bore 53 is a coil spring 57. Mounted on the upper end of the bolt 55 is a member 58 the lower face of which is provided with a plurality of rack teeth 59 adapted for inter-engagement with the aforementioned rack teeth 52 and are permitted to ride upwardly upon the rack teeth 52 through the medium of the resiliency of the coil spring 57. The upper portion of the member 58 is squared as at 60 to be received by the opening 61 in an operating wrench 62 which provides means for driving the cable drum without the use of the aforementioned dogs if desired.

The operating wrench 62 is further provided with a smaller squared opening 63 to receive the upper squared end 64 of the power plug 15, and is used as an operating means therefor in lieu of the lever 26. 110

means therefore in lieu of the lever 20. One end of the lower plate 6 is provided with a hook member 65 and the opposite end of both of said plates are brought together as at 66 and are provided with registering openings 66' to receive a suitable anchoring means, not shown. 115

The operation of the device is as follows:

The frame is anchored by any suitable means secured in the opening 66' to prevent 120 movement of the frame under strain.

The free end of a cable is secured in any suitable manner to hook 65, and is passed through a block which in turn is secured to the stump to be pulled. The cable is passed rearwardly and is wound around the cable drum 12, the wrench 62 being applied to the squared end 60 for this purpose. 125

After the cable has been wound upon the drum sufficient to start operation of the ma- 130

chine, the operating wrench is removed from the squared end 60 and is attached to the lever 26.

Upon oscillatory movement of the lever 26 the dogs 27, 28 and 31 are caused to engage their respective rack teeth to drive the drum in a rotary direction.

If the strain becomes of too great proportion, the operating wrench 62 is removed from the operating lever 26, and its smaller opening 63 is passed over the squared end 64 of the power plug 15 for the purpose of obtaining greater leverage to operate the drum through the medium of the dogs 21 15 and 22.

When it is desired to rotate the drum in the opposite direction for the purpose of removing the cable therefrom, the handle 38' of the member 38 is grasped, and said member is moved about its pivot until its curved end 39' engages the lug 27' on the dog 27. Upon further movement of the member 38 the portion 40' thereof engages the lug 23 on the dog 22 and causes the same 25 to engage the dog 28 to move the latter as well as the dogs 22 and 27 out of engagement with their respective rack teeth.

By grasping the handle 33' of the member 33 and moving the member 33 in the direction of the arrow A in Fig. 10, said member is caused to engage the dog 21 to move it out of engagement with its respective rack teeth, thus releasing the cable drum and permitting the same to rotate to permit of 35 the removal of the cable to prepare the machine for a subsequent operation.

From the foregoing it will be understood that three different speeds are obtained *i. e.* one when the operating wrench 62 is applied to the drum direct, one when it is applied to the rigid lever 26, and a third when the operating wrench is applied to the squared end 64 of the power plug 15.

Having thus described the invention, what 45 is claimed is:

1. A stump puller comprising a pair of plates secured in spaced relation, a cable drum rotatable between said plates, an inner and outer circular rack carried by one end 50 of the cable drum, a power plug rotatably mounted between the plates and having its upper extremity squared and projecting above the top plate, a lever pivotally carried by the power plug, a pair of dogs pivoted to the power plug and having their free ends 55 engaging the outer circular rack, a dog pivoted to the power plug and having their free ends engaging the inner circular rack, a dog pivoted to the power plug and having their free ends 60 engaging the outer circular rack, means for maintaining the last mentioned dogs in engagement with their respective rack teeth, means for maintaining the first mentioned dogs in engagement with their respective rack teeth, means for 65 maintaining the first mentioned dogs in engagement with their respective rack teeth, and means for moving the dogs out of engagement with their respective rack teeth.

2. A stump puller comprising a pair of plates secured in spaced relation, a cable drum rotatable between said plates, an inner and outer circular rack carried by one end of the cable drum, a power plug rotatably mounted between the plates and having its upper extremity squared and projecting above the top plate, a lever pivotally carried by the power plug, a pair of dogs pivoted to the power plug and having their free ends 70 engaging the outer circular rack, a dog pivoted to the power plug and having its free end 75 engaging the inner circular rack, a dog pivoted to the power plug on one side of the power plug and having its free end engaging the outer circular rack, a coil spring connecting each of said last mentioned dogs to maintain them in engagement with their respective rack teeth, a U-shaped spring engaging the first mentioned dogs to maintain them in engagement with their respective rack 80 teeth, and means for moving said dogs out of engagement with their respective rack teeth.

3. A stump puller comprising a pair of plates secured in spaced relation, a cable drum rotatable between said plates, an inner and outer circular rack carried by one end of the cable drum, a power plug rotatably mounted between the plates and having its upper extremity squared and projecting above the top plate, a lever pivotally carried by the power plug, a pair of dogs pivoted to the power plug and having their free ends 90 engaging the outer circular rack, a dog pivoted to the power plug and having its free end 95 engaging the inner circular rack, a dog pivoted to the power plug on one side of the power plug and having its free end engaging the outer circular rack, a dog pivoted to the power plug and having its free end 100 engaging the inner circular rack, a dog pivoted to the power plug and having its free end 105 engaging the outer circular rack, resilient means for maintaining the last mentioned dogs in engagement with their respective rack teeth, and carried by the dogs, resilient means for maintaining the first mentioned dogs in engagement with their respective rack teeth, means pivotally carried by one of the plates for disengaging three of the dogs with their respective rack teeth, and means carried by the power plug for disengaging the fourth dog with its respective rack teeth.

4. A stump puller comprising a pair of plates secured in spaced relation, a cable drum rotatable between said plates, an inner and outer circular rack carried by one end of the cable drum, a power plug rotatably mounted between the plates and having its upper extremity squared and projecting above the top plate, a lever pivotally carried by the power plug, a pair of dogs pivoted to the power plug and having their 110 115 120 125 130 free ends engaging the outer circular rack, a dog pivoted to the power plug and having their free ends engaging the inner circular rack, a dog pivoted to the power plug and having their free ends engaging the outer circular rack, means for maintaining the last mentioned dogs in engagement with their respective rack teeth, means for maintaining the first mentioned dogs in engagement with their respective rack teeth, means for maintaining the first mentioned dogs in engagement with their respective rack teeth, and means for moving the dogs out of engagement with their respective rack teeth.

free ends engaging the outer circular rack, a dog pivoted to the pivoted lever on one side of the power plug and having its free end engaging the inner circular rack, a dog pivoted to the pivoted lever on the opposite side of the power plug and adapted to engage the outer circular rack, resilient means for maintaining the last mentioned dogs in engagement with their respective rack teeth, and 10 carried by the dogs, resilient means for maintaining the first mentioned dogs in engagement with their respective rack teeth, means pivotally carried by one of the plates for disengaging a predetermined number of 15 the dogs with their respective rack teeth and maintaining them in said disengaged position, and means carried by the power plug for disengaging one of said dogs with its respective rack teeth, and maintaining said 20 dog in its disengaged position.

5. A stump puller comprising a pair of spaced plates, means for securing the plates in spaced relation, a cable drum revolvably mounted between the plates, a platform intermediate of the plates, a power plug supported by the platform, means for limiting the rotary movement of the power plug, a lever pivotally mounted on the power plug, means carried by the lever and adapted to 30 engage the cable drum to rotate the same, means carried by the power plug and adapted to engage the cable drum to operate the same, and means for operating said power plug.

35. 6. A stump puller comprising a pair of spaced plates, means for securing the plates in spaced relation, a cable drum revolvably mounted between the plates, a platform secured intermediately of the plates, a power 40 plug supported on said platform, means carried by the platform for limiting the rotary movement of the power plug, a lever pivotally mounted on the power plug, a pair of pawls carried by the lever and adapted to 45 engage the cable drum to rotate the same, a pair of pawls carried by the power plug and adapted to engage the cable drum to rotate the same, means for retaining the first mentioned pawls in engagement with 50 the cable drum, means for moving said pawls out of engagement with the cable drum, and means for operating the power plug.

7. A stump puller comprising a pair of 55 spaced plates, a cable drum revolvably mounted between the plates, a plurality of rack teeth carried by the cable drum, a power plug mounted between the plates, a lever pivotally carried by the power plug, 60 means pivoted to said lever and adapted to engage the rack teeth of the drum to rotate the same, means carried by the power plug

and adapted to engage the rack teeth of the drum to rotate the same, and means for operating the power plug.

65 8. A stump puller comprising a pair of spaced plates, a cable drum revolvably mounted between the plates, an inner and outer series of rack teeth carried by one end of the cable drum, a power plug mounted between the plates, a lever pivotally carried by the power plug, means carried by the pivoted lever and engaging the inner and outer series of rack teeth of the drum to rotate the drum, means carried by the power plug 70 and engaging the outer series of rack teeth of the circular drum to rock the drum, and means for operating the power plug.

75 9. A stump puller comprising a pair of spaced plates, a drum revolvably mounted between the plates, an inner and outer series of rack teeth carried by one end of said drum, a power plug mounted for partial rotary movement adjacent said drum, a lever pivotally carried by the power plug, means 80 carried by the lever for engagement with the inner and outer series of rack teeth to rotate the drum, resilient means for maintaining said rack engaging means in engagement with the rack, means for disengaging said rack engaging means with the rack, means carried by the power plug for engagement with the outer rack teeth to rotate the drum, means for maintaining the last mentioned rack engaging means in engagement with the rack teeth, means for disengaging said last mentioned rack engaging means with the rack teeth, and means for operating the power plug.

85 10. A stump puller comprising a pair of spaced plates, a drum revolvably mounted between the plates, an inner and outer series of rack teeth carried by one end of the drum, a power plug mounted between the plates, a lever pivotally carried by the power plug, 100 pawls pivoted to said lever and adapted to engage the inner and outer series of rack teeth, means carried by the pawls for maintaining them in engagement with the inner and outer rack teeth, means adapted 105 to engage the pawls to move them out of engagement with the inner and outer rack teeth, a plurality of pawls carried by the power plug and adapted to engage the outer series of rack teeth, resilient means 110 engaging said pawls to maintain them in engagement with the outer series of rack teeth, means carried by the power plug for moving one of said pawls out of engagement with the outer series of rack teeth, and 115 means for operating said power plug.

120 In testimony whereof I affix my signature.

GEORGE DRAZICK.
